UNITED STATES PATENT OFFICE.

WILLIAM H. LOPP, OF WASHINGTON, DISTRICT OF COLUMBIA.

DESIGN FOR A TEA-CUP.

SPECIFICATION forming part of Design No. 31,967, dated December 12, 1899.

Application filed November 14, 1899. Serial No. 736,995. Term of patent 3½ years.

To all whom it may concern:

Be it known that I, WILLIAM H. LOPP, a citizen of the United States, residing at No. 906 K street, Northwest, Washington, District of Columbia, have invented and produced a new and original Design for Tea-Cups, of which the following is a specification, reference being had to the accompanying drawings, forming a part thereof.

10 Figure 1 is a plan view of a tea-cup, showing my new design. Fig. 2 is a side view.

As shown in the drawings, the leading or material feature of my design consists of the signs of the zodiac in the bottom and on the 15 sides of the cup, together with two male and two female figures, showing the heads, in con-

nnection with heart, diamond, club, and spade, inside of the circle showing the signs of the zodiac aforesaid.

Having described my invention, what I claim as new, and desire to secure by Letters Patent, is—

The design for a tea-cup, as herein shown and described.

In testimony whereof I have signed my name to this specification in the presence of two subscribing witnesses.

WILLIAM H. LOPP.
